UNITED STATES PATENT OFFICE

RALPH A. HERBRUCK, OF DAYTON, OHIO.

APPARATUS FOR USE WITH HOT-AIR HEATING SYSTEMS.

Application filed February 2, 1927. Serial No. 165,390.

The invention relates to apparatus for use with hot air registers in connection with house heating furnace systems. It often happens that, due to wind direction or other cause, it is impossible to secure a proper or sufficient flow of heated air to a particular room. The present invention is designed to provide a simple, inexpensive means for overcoming this difficulty, or to secure an extra amount of heat in some particular room without disturbing the register shutters in the other rooms or going to the basement and changing the regulation of the various dampers in the hot air supply pipes. Briefly stated, this is accomplished by the use of a casing carrying an electric fan and having a suitable outlet in its side through which the fan discharges, the casing being open at the bottom and also on one side, so that the casing may be either seated over a floor register or may be placed with its open side in opposition to a wall register. When the casing is in use over a floor register, the opening in its side is closed by a suitable door or shutter. In this manner the fan is made to provide a suction in the casing, and so draw heated air from the register. Certain embodiments of the invention are shown in the accompanying drawing, 30 wherein:

Figure 1 is a perspective view of the apparatus. Fig. 2 is a vertical section through the apparatus in one of its positions of use over a floor register. Fig. 3 is a vertical section through the apparatus in its other position of use with a wall register. And Figs. 4 and 5 are views similar to Figs. 1 and 2, respectively, but showing a modification involving a different mounting of the fan.

Referring to Figs. 1 and 2, 1 is a floor register with the hot air pipe 2 leading thereto, and 3 is a sheet metal casing, open at the bottom, and seated upon the floor 4. The casing is provided with a shelf 5, which supports the electric fan 6, and with an outlet opening 7 forward of the fan. A second opening 8 is provided through the rear wall of the casing in opposition to the fan. When the device is used over the floor register, as indicated in Fig. 1, the opening 8 is closed by a suitable door 9, such door being preferably guided for horizontal movement in the guides 10. The path of the air, as it is sucked from the pipe 2 by the fan and discharged through the casing, is shown by the arrows.

When the apparatus is used with a wall register 12, as shown in Fig. 3, the door 9 over the opening 8 is removed, the bottom opening to the casing being closed by the floor 13, and the direction of the flow of air is as indicated by the arrows. Even though the rear wall of the casing does not engage the wall 14 of the room surrounding the register, the draft produced by the fan is sufficient to produce the desired result. The apparatus may in this manner be used with both types of register, which are ordinarily found in one residence, the floor registers being used on the lower floor and the wall registers on the upper floors.

Figs. 4 and 5 show a construction similar to that of Figs. 1 to 3, except as to the mounting of the fan 15. This mounting comprises a ring 16 riveted, or fastened by screws, to the casing 17 around the outlet opening, to which are secured the spider arms 18 secured at their inner ends to the casing of the fan. This mounting has certain advantages as compared with that of Figs. 1 to 3, but has to be made special and supplied with the casing, while the apparatus of Figs. 1 to 3 may be made and sold without the fan equipment, which may be supplied by the purchaser, as any ordinary house fan may be used upon the shelf. A handle 19 is provided upon the top plate of the casing in both forms of apparatus for convenience in moving such apparatus from place to place.

What I claim is:

1. In combination in hot air heating apparatus, a portable casing open on the lower side and adapted to rest upon a floor and surround a hot air register, and also open its rear side, so that such opening may be placed in opposition to a wall register, a door for such last opening, and an electric fan in the casing facing away from such last opening, an outlet opening being provided in the front wall of the casing in line with the fan.
2. In combination in hot air heating apparatus, a portable casing open on its lower side and on its front side and adapted to rest upon a floor and surround a hot air register, and also open on its rear side, so that such opening may be placed in opposition to a wall register, a door for such last opening, and an electric fan in the casing facing through the opening in the front wall and supported by the casing.

3. In combination in hot air heating apparatus, a portable casing open on its lower side and on its front side and adapted to rest upon a floor and surround a hot air register, and also open on its rear side, so that such opening may be placed in opposition to a wall register, a door for such last opening, a shelf supported by the casing below the opening in the front wall of the casing, and an electric fan seated removably on such shelf and facing through the opening in the front wall of the casing.
4. In combination in hot air heating apparatus, a portable casing open on its lower side and on its front side and adapted to rest upon a floor and surround a hot air register, and also open on its rear side, so that such opening may be placed in opposition to a wall register, a door for such last opening, and an electric fan in the casing facing through the opening in the front wall and supported by the casing, the openings through the front and rear walls of the casing being in substantial alinement.

In testimony whereof, I have hereunto subscribed my name this 28th day of January, 1927.

R. A. HERBRUCK.
